UNITED STATES PATENT OFFICE.

ELIZABETH PARKER KELLEY, OF PHILADELPHIA, PENNSYLVANIA.

MEDICINAL COMPOUND FOR EXTERNAL USE AS A PLASTER OR OINTMENT.

1,414,815.

Specification of Letters Patent.

Patented May 2, 1922.

No Drawing.

Application filed February 25, 1919. Serial No. 279,169.

To all whom it may concern:

Be it known that I, ELIZABETH PARKER KELLEY, a citizen of the United States of America, and resident of Philadelphia, 5 county of Philadelphia, State of Pennsylvania, have invented certain new and useful Improvements in and Relating to Medicinal Compounds for External Use as a Plaster or Ointment, of which the following 10 is a specification.

This invention relates to medicinal compounds; and the objects and nature of the invention will be readily understood by those skilled in the art in the light of the 15 following explanation of an embodiment of the invention and a method of compounding the same.

An object of the invention is to produce a new compound that will possess peculiar 20 medicinal virtues when employed as a poultice, plaster or ointment in the treatment of infected, inflamed or diseased portions or organs of the human body, and particularly when employed as a plaster or poultice 25 compound on the chest and back in the treatment of pneumonia cases.

I have discovered that a plastic or poultice compound that includes "Isarol" or its 30 medical equivalent ichthyol, and certain other ingredients or their medical equivalents, is of peculiar medical value and assistance in the treatment of pneumonia cases, when applied to the exterior of the body 35 over the chest cavity.

For instance, I find that a compound that 40 includes "Isarol" (or ichthyol); belladonna; and a suitable body, vehicle or carrier such as benzoinated lard, possesses marked medicinal value when used as an exterior poultice, plaster or ointment over or adjacent to 45 the affected interior organ or portion of the body particularly in pneumonia cases.

In preparing this compound, I usually mix liquid "Isarol" with benzoinated lard 45 in the proportions of approximately one part of "Isarol", by weight, with approximately three parts of benzoinated lard, by weight.

I also mix extract of belladonna (say in 50 the gum-like or solid form) with benzoinated lard, in the proportions of approxi-

mately one part of belladonna extract to three parts of lard, by weight.

I thus form a plastic or ointment-like "Isarol" mass, and a plastic or ointment- 55 like belladonna mass.

I then form my new plaster or poultice compound by thoroughly mixing together suitable proportions of the "Isarol"-lard and the belladonna-lard masses. These two 60 masses are mixed together in approximately the proportion of two thirds "Isarol"-lard mass to one third belladonna-lard mass by weight, although I do not wish to so limit my invention to these identical proportions. 65

The resulting compound is plastic or unc- 70 tion-like, and in use in pneumonia cases, the compound is spread over the chest and back to form a layer or plaster and is then covered with absorbent cotton or the like.

The benzoinated lard apparently performs an important function in so softening the affected parts and mucous mass as to render the same more susceptible to the cooper- 75 ating medicinal functions of the "Isarol" in "drawing" and the belladonna in "drying up."

As at present advised by experience, I prefer to employ ichthyol instead of "Isarol", but now employ "Isarol" which is the medicinal equivalent of ichthyol, because of the 80 present difficulty of securing ichthyol in this country.

It is my understanding that "Isarol" is in the nature of a trade name for purified ichthyol, a material that is the medicinal 85 equivalent of ichthyol.

While I prefer to employ benzoinated lard as the vehicle as it is superior to any other ingredient for this purpose, that I have as yet discovered, yet I do not wish to 90 limit myself strictly thereto.

Also, I do not wish to limit myself to the various proportions herein stated nor to any particular extract percentages although I usually employ twenty five per cent extracts 95 of belladonna and "Isarol" as commonly found on the market.

What I claim is:—

1. A medicinal plaster, ointment, or poultice for external use, embodying ichthyol, 100 belladonna, and benzoinated lard.
2. A medicinal plaster, ointment or poultice

tice for external use, embodying ichthyl, belladonna, and a medicinal vehicle, in about the proportions of one part belladonna to two parts ichthyl, and about one 5 part ichthyl and belladonna to three parts vehicle.

3. A medicinal compound for external use as a plaster or poultice, embodying ichthyl,

belladonna, and benzoinated lard, the proportion of benzoinated lard being approximately three times the combined proportions of ichthyl and belladonna, and the proportion of ichthyl being approximately twice the proportion of belladonna. 10

ELIZABETH PARKER KELLEY.
